UNITED STATES PATENT OFFICE.

SAMUEL B. STEWART, JR., OF SCHENECTADY, NEW YORK, ASSIGNOR TO
GENERAL ELECTRIC COMPANY, A CORPORATION OF NEW YORK.

CURRENT-COLLECTOR.

No. 853,838.

Specification of Letters Patent.

Patented May 14, 1907.

Application filed August 1, 1906. Serial No. 328,668.

To all whom it may concern:

Be it known that I, SAMUEL B. STEWART, Jr., a citizen of the United States, residing at Schenectady, county of Schenectady, State 5 of New York, have invented certain new and useful Improvements in Current-Collectors, of which the following is a specification.

This invention relates to electric railways and especially to the apparatus mounted on to an electric railway vehicle, for collecting currents from an overload conductor or a third rail.

It is sometimes found desirable or necessary to operate one portion of a railway by means of current supplied by a third rail arranged near the roadbed, and at another portion, as at crossings and similar places where the third rail would obstruct the passage across the way and be unsafe, by current supplied by a trolley wire or overhead conductor. The moving vehicle must accordingly be equipped with collecting means for co-operating with both forms of supply conductors. Means must be provided for reTRACTING the collecting devices, so that the idle one may rest out of the way and be prevented from striking any structures erected adjacent its path of travel.

The object of my invention is to provide a simple and efficient means for automatically retracting the current collector at desired points along the line of travel.

For the sake of convenience, I have illustrated in the accompanying drawing, my invention applied to an overload collector but it is equally applicable to a contact shoe of a third rail system.

I have chosen to show two current collectors and two engineer's valves, such as are at present being introduced in heavy service, though it is evident that but one may be used if desired. As both are alike, a description of one will suffice.

The current collector is properly of the lazy-tongs variety. The shoe 1 slides in contact with the overhead conductor 2 which is provided with a depressed portion 3 where it is desired to retract the collector. The shoe is pivoted to the upper members 4 of two toggles, whose lower members 5 are pivoted on a pedestal 6 mounted on the roof of the electric vehicle. The adjacent ends of the lower members 5 are provided with sector gears 5'

which intermesh so that the members move in unison. The lower ends of the upper members extend beyond their pivots and strong springs 7 are attached thereto and to the lower members 5 at or near their pivots. These springs urge the shoe upwardly against the conductor, and in order to insure 60 good electrical connection between the shoe 1 and the pedestal 6, while allowing the shoe to move freely up and down, flexible leads 8 are connected to the shoe and pedestal.

The pedestal is hollow and contains a cylinder 9 in which fits a piston 10 connected by a piston rod 11 with a yoke 12 which stands above the lugs 13 on the lower members of the toggles. A strong helical spring 14 is compressed between the top of the pedestal and the piston and urges the latter downward with sufficient force to overcome the upward thrust of the springs 7, and pull the shoe away from the conductor. The lower end of the pedestal is closed as by a screw plug 15 so that a chamber is formed under the piston to which compressed air or other pressure fluid can be admitted through a pipe 16. The area of the piston is sufficient to enable the air to lift it against the tension 80 of the spring, and hold the yoke out of engagement with the lugs 13.

The air is stored in a suitable reservoir and the pressure is maintained by a suitable air compressor (not shown). The admission of 85 air to the cylinder in which the piston works, and its exhaust therefrom, are controlled by an engineer's valve or valves 17 located at some point or points on the vehicle, convenient to the driver. Inasmuch as electric vehicles are usually arranged to run either end foremost, there is a valve located at each end of the vehicle, and each valve simultaneously controls both current collecting devices in case more than one is used.

The engineer's valves 17 each comprises a cylinder 18 in which is a piston 19 provided with a hand plunger 20 and connected to a slide valve 21 which operates to open and close connections between exhaust port 22 100 and the delivery port 23. The supply port 24 on the end of the valve chamber opposite the piston, is connected with a pipe 25 which leads to the source of compressed air, and at the other end of the chamber is a vent port 105 26 which is connected through the pipe 27

with a pilot valve 28. The pilot valve 28 is supported at one side of the collector pedestal 6, and comprises a simple valve box 29 having a horizontally movable valve 30 therein normally held against the seat about a vent port 31 by a spring 32 compressed between the back of the valve 30 and the back side of the box 29. The stem 33 of the valve extends through the port 31 and engages the lower end of a lever 34 pivoted on the top of the valve box 29 and normally held in vertical position by a spring 35, so that its upper end may be engaged and deflected outwardly by a shoulder 36 carried by one of the lower toggle arms 5 when the shoe 1 is moved below its normal working position by the depressed portion 3 of the conductor.

The operation of the apparatus is as follows: The compressed air supplied to the engineer's valve 17 by pipe 25 fills the entire space within the cylinder 18, and on both sides of the piston 19, the latter being purposely left unpacked so that the air may leak thereby, and upon the opening of the pilot valve 28 the air to the right of the piston 19 escapes through the vent port 26 and pipe 27, unbalancing the piston and allowing it to move to the right by the air pressure at the left side thereof and carrying with it the slide valve 21 into position to connect the exhaust port 22 with the delivery port 23 and permitting the release of the air in the collector pedestal. This allows the spring 14 to force the yoke 12 down and with it the toggle levers 4, 5 and collector shoe 1. When it is desired to raise the collector shoe 1, the hand plunger 20 is drawn to the left and carries with it the piston 19 and slide valve 21 into the position indicated in the drawing, to close the exhaust port 22 and open the delivery port 23 to the air supplied by pipe 25 from the source of compressed air and lifts the yoke 12 from engagement with the toggle levers, allowing the latter to move upwardly under the tensions of springs 7.

In order to control both current collectors from a single engineer's valve 17, the vent pipes 27 and the delivery pipes of both collectors are connected as indicated, and to prevent the air in one valve 17 from exhausting through the other, after the slide valve 21 in the former has been moved into closed po-

sition, a double check valve 37 is arranged in the delivery pipes 16.

I do not desire to restrict myself to the particular form of arrangement of parts herein shown and described, since it is apparent that they may be changed and modified without departing from my invention.

What I claim as new and desire to secure by Letters Patent of the United States is,—

1. The combination with a suspended conductor and a current collector for electric vehicles, of a retractor for the collector, means controlled by the movement of the collector out of its normal working position for actuating said retractor, and means disposed at desired intervals upon said conductor for moving said collector out of its working position.

2. The combination with a suspended conductor and a current collector for electric vehicles, of a spring pressed retractor for said collector, means for holding said retractor in inoperative position, means controlled by the movement of the collector out of normal working position for releasing said holding means, and means disposed at desired intervals upon said conductors for moving said collector out of its working position.

3. The combination with a suspended conductor and a current collector for electric vehicles, of a spring pressed retractor for said collector, pneumatic means for holding said retractor in inoperative position, a pilot valve for said pneumatic means actuated by the movement of the collector out of its normal working position and means disposed at desired intervals upon said conductor for moving said collector out of its working position.

4. The combination with a current collector of a retractor therefor, a fluid pressure system for actuating said retractor, an engineer's valve for controlling said fluid pressure, and a pilot valve actuated by the abnormal movement of said collector and automatically controlling the said engineer's valve.

In witness whereof, I have hereunto set my hand this 31st day of July, 1906.

SAMUEL B. STEWART, JR.
